UNITED STATES PATENT OFFICE.

BRITTON E. BYRD, OF DURHAM, NORTH CAROLINA, ASSIGNOR, BY MESNE ASSIGNMENTS, TO MILL DEVICES COMPANY, OF LYON PARK, NEAR DURHAM, NORTH CAROLINA, A CORPORATION OF NORTH CAROLINA.

YARN-SIZING MACHINE.

1,214,998.

Specification of Letters Patent.

Patented Feb. 6, 1917.

Application filed November 10, 1914. Serial No. 871,318.

To all whom it may concern:

Be it known that I, BRITTON E. BYRD, residing at Durham, in the county of Durham and State of North Carolina, have invented 5 certain new and useful Improvements in Yarn-Sizing Machines, of which the following is a specification.

This invention has reference to machines for slashing and sizing yarns or threads 10 prior to the use of the same in a loom, and in the practical operation of which the threads or yarn are drawn from the thread beams at one end of the machine, caused to travel into and through the sizing substance, 15 thence to means that removes or squeezes the superfluous sizing substance from the said threads, and thence caused to travel over drying means and finally passes along to and taken up by the loom beam.

20 In the use of machines of the general character stated usually when the machine is stopped, that is the passing of the thread from the thread beams to the take-up or loom beam is arrested, if but for a very 25 short time, those portions of the yarn or threads in the act of sizing and which have not been passed through the squeezing rolls, become hardened and injured, by reason of the sizing material drying thereon and 30 hence before the machine can be again started, to effect the desired sizing operation, all of the yarn between the sizing means and the take-up or loom beam must be cut out and removed, causing, as it were, 35 the total loss of such lengths of the yarn, and also much loss of time on the part of the attendant.

My invention primarily has for its object 40 to provide certain improvements in machines of the type referred to in which the stopping of the machine for any length of time prior to the filling of the loom beam with the sized yarns does not necessitate the cutting out of any portion of the yarn and 45 by which, in case of stoppage of the machine, the yarn or threads can be so manipulated that danger of the sizing material hardening on the threads is entirely overcome and the said threads thereby held in

readiness when again starting the machine 50 for a proper passage through the sizing material, the squeezing means, the drying devices and to the take-up or loom beam.

With other objects in view, that will hereinafter appear, my invention embodies the 55 peculiar features of construction and novel arrangement of the parts that constitute my improved yarn sizing machine, all of which will be hereinafter first described in detail, then be specifically pointed out in the appended claims and illustrated in the accompanying drawings in which:

Figure 1 is a side elevation of a yarn sizing or slashing machine that embodies my 60 improvements.

Fig. 2 is a detail enlarged section of the 65 sizing tank.

Fig. 3 is a transverse section of the sizing tank, taken substantially on the line 3—3 on Fig. 2 and illustrates the manner in which 70 the sizing roll is mounted on the said tank.

Fig. 4 is a perspective view of the slack 75 take-up devices hereinafter referred to.

Fig. 5 is a diagrammatic vertical sectional view that shows the yarn loop forming 80 member at the dropped or lower position for taking up the "slack" in the yarn threads for causing that portion of the sized yarn that has not reached the squeeze rolls to pull through the said rolls.

Figs. 6 and 7 are detail views of parts of the rockably mounted thread or yarn guide that forms a part of the aforesaid take-up devices.

Fig. 8 is a perspective view of that end of 85 the machine in which is mounted the loom beam and the tension devices hereinafter specifically referred to.

Fig. 9 is a section on the line 9—9 on Fig. 8, showing the tension device adjusted for 90 applying the desired tension to the sized threads, as they travel toward the take-up or loom beam.

Fig. 10 is a similar view, the parts being 95 shown under another adjustment.

Referring now more particularly to Fig. 1 of the drawings, 1 designates the main frame of the machine, 2 the usual kettle or

tank in which is contained the starch or sizing substance and located at one end of the framing.

3—3 designate the lower squeeze rollers 5 journaled in the side beams of the main frame above the tank 2 and with which cooperate the upper squeeze rollers 4, which, when the machine is in operation, engage the rollers 3 and which are removably mounted in the slotted bearings 5 on the sides of the frame 1, the bearings opening upwardly so as to permit the squeeze rollers to be unshipped therefrom. To provide for supporting the upper squeeze rollers 4 when removed from their bearings 5—5, other slotted bearings 6—6 are mounted on the frame adjacent the bearings 5—5 and they extend upwardly to a higher point than the bearings 5—5 so as to support the rollers 4 away from the lower rollers 3.

10 designates the usual main drying cylinder mounted on the frame 1 and 11 designates a smaller drying cylinder located between the tank 2 and the large cylinder 10. 25 9 designates a direction or guide roller mounted on the rear end of the machine over the inlet edge of the tank 2 and 7 denotes a slashing or sizing roll, whose journals are mounted in grooves 8^a in the vertical members 8 of the frame 1, so that the said roll may be lowered to cause the yarns to be sized to run through the sizing material in the tank 2 during the operation of sizing and when elevated to permit the said 30 35 yarns to be run without coming in contact with sizing material.

13—14—15 designate the yarn beams mounted on a frame 31 suitably located with reference to the tank 2 and from which the 40 yarns, indicated by *a* on Fig. 1, pass to the sizing tank.

The several parts of the sizing machine shown in the drawings, so far described, are of a well-known construction, and *per se*, 45 they form no part of my invention, since my said invention is especially confined to the yarn take-up and the yarn tension devices, and the means for maintaining the yarn thread in a taut or straight line in its 50 passage from the squeeze rolls to the larger or main drying drum, and which I shall now proceed to describe.

A pair of vertically disposed standards are secured to opposite sides of the frame 55 1 at a point between the sizing tank and the drying cylinder 12 and each of such standards includes a lower or fixed member 32 and an upper member 32^a supported by and having vertical adjustment in the fixedly 60 held members 32. The upper members 32 each have a vertical groove 34 on the inner face, that extends from the upper to the lower end thereof.

36—37 designate a pair of tubular guides

or rollers, the ends of which receive short 65 stub journals 38—38 on the opposite ends of the rocker arms 39, one of which is pivotally mounted on the outer face of the upper ends of the standard members 32^a, and the pivot members 35 for such arms 39 are adjustably connected to the said members 32^a, as shown.

The parts last described form a part of the take-up devices and at this point it should be stated the threads pass over the 75 tubular guide rollers 36—37 and since the said rollers are mounted in rocker arms 39 it follows that the said roller guides may be adjusted and shifted to the required angle, relatively to the line of angle, the 80 threads take as they pass from the squeeze rolls to the large or main drying drum and thus keep the yarns in a perfectly straight line from the said squeeze rolls to the drier.

Coöperating with the rollers 36—37 is a 85 tubular guide roller 40 mounted on the stub journals 41 on the inner face of heavy bars 42 adapted for slidably engaging the grooves in the standard members 32^a and the said 90 bars each include a weighted member 43 hingedly joined with the member 42 to fold out in alignment with the said member 42 when it is desired to lower the members 42 down on the grooved members 32^a and to 95 swing over, at right angles over the upper end of the members 32^a, to support the roller 40 at a point above the rollers 36 and 37 and out of engagement with the threads during the sizing operation.

44 designates the loom beam that is 100 removably mounted in bearings at the front end of the machine and upon which the sized yarn is wound.

The tension devices in my improved construction of yarn sizing machine, and which 105 are best shown in Figs. 8, 9 and 10 of the drawing, consist of a pair of horizontally disposed friction rollers 50 located one at each side of a roller 16, which is of larger diameter than the rollers 50 and located 110 between such rollers and below the same, and the said roller 16 has bearings in the main frame of the machine.

Rollers 50—50 are loosely supported at their ends above hanger bars 51—51, adjustably mounted on the lower ends of hanger arms 52—52, the upper ends of which are pivotally hung on stud bearings 53 that project laterally from a lever member 54 that has other lateral studs 55 for adjustably seating in any set of a series of a set of bearings 56 in the upper edges of a housing 57 removably mounted on the main frame of the machine and including an adjustable clamping device 58, the latter being 120 provided for attaching the housing to frame portions of different widths.

Each hanger arm has a notch 59 so ar-

ranged, relatively to its pivotal connection with the lever members 54 to slip over and interlock with the studs 55 on the lever arms when the latter is swung over to raise the 5 rollers 50 to provide for the desired tension on the yarn threads during the operation of sizing and for holding the said rollers 50 locked on the elevated position, it being understood by reference to Fig. 9, that when 10 the lever 54 is swung over to the position shown, the pivotal connections for the hanger arms are beyond the line of center of the pivotal bearing for the lever 54.

From the foregoing taken in connection 15 with the drawings, the complete construction and the advantages of my invention will be readily apparent.

In operation of slashing or sizing the threads, and assuming the drying cylinders 20 to be revolving in the direction indicated by the arrows, the warp threads are drawn from the beams and caused to travel over the guide roller 9, under the sizing roller 7, and the said roller 7, being now at its lower position 25 causes the threads to contact with the sizing material in the tank 2, from which point the yarn threads pass between the upper and lower squeeze rollers 3 and 4, which serve to remove the superfluous sizing 30 material or starch from the yarns, the sized yarns being dried as they pass over the cylinders 10—12, from which they pass over guide rollers 61—62, to the tension devices and thence to the loom beam, reaching the 35 latter in a dry condition, suitable for use in the loom.

As before stated, in other types of sizing machines, when the operation of sizing is 40 temporarily stopped, the yarn between the sizing tank to the loom beam is cut out and wasted. In the construction of sizing machine shown in the drawings, when the machine is stopped, at any time prior to filling the loom beam, the operator turns up the 45 weighted member 43 in line with the member 42, to allow the said member 42 to drop and to bring the roller 40 down between the rollers 36—37, to cause the roller 40 to engage the yarns and as the said 50 roller 40 is of greater weight than the sizing roller 7, it produces a pendent loop or bight in the yarn and in doing so takes up slack between the guide roller 9 and the squeeze rollers, and hence causes the yarn to raise 55 the sizing roller out of the sizing tank and those portions of the yarn to which sizing has been applied, and which had not been reached by the squeezing rollers, will be caused, by the taking up of the slack thereon, 60 by the roller 40, to be drawn between the squeeze rollers and relieved of superfluous sizing material, and also be thereby kept from becoming hardened and injured by drying. It should be stated that the draw-

ing of the threads through the squeezing 65 rolls when applying the take-up to form the loop or bight, as stated, is positively effected, by reason of the tension device at the loom beam end holding the threads from pulling backward, the slack that forms the loop being provided by pulling the yarns forwardly from the sizing tank, (see arrow 'y' on Fig. 5).

After the slack in the yarns has been taken up, the operator unships the upper 75 squeeze rollers from the bearings 5 and places them in bearings 6 to thereby entirely remove the yarn from contact with the lower squeeze rollers. After the rollers have been thus placed, the operator swings the 80 lever of the tension devices to the position shown in Fig. 9, which drops the rollers at each side of the roller 16 and thus relieves the tension of the yarn.

The operator then turns the yarn carrying beams at the tank end and winds the 85 yarn back again until the desired portions to be sized are positioned for being advanced to and through the sizing material.

It should be stated that when the machine 90 is positively driven by applying power direct to either of the drying cylinder shafts, the tension devices are adjusted for the free passing of the yarn threads between the co-acting friction rolls, but when the driving 95 power is indirect, for example, applied to the take-up or loom beam, as is done in some yarn sizing machines, the said tension devices are operatively adjusted to maintain a regular or even pull on the threads as they 100 pass up from the driers to the tension rolls.

Another and important advantage in making the standards vertically adjustable and mounting the transverse guide rollers over which the threads pass on rockable arms, is 105 that provision is made for adjusting the said rocker arms to any height relatively to the line of feed of the threads from the squeeze rolls to the drying cylinders of different sizes and thus provide, as it were, for a yielding bearing for the threads that overcomes 110 strain on the threads by having them pass in other but straight line from the squeeze rolls to the drying cylinders.

While I have shown and described the tension devices that form a part of my complete 115 yarn sizing machine, I make no claim in this application to the said tension devices since they form the subject matter of my co-pending application, Serial No. 77,601, filed February 11, 1916, and which is a divisional part of this application.

What I claim is:

1. In a yarn sizing machine, the combination with the sizing tank, the sizing roller, 125 the squeezing rolls, the means for drawing the yarn through the said rolls and a tension device to hold the yarn from backward

4 movement; of a mechanism for raising the said sizing roller from immersion and advancing the yarn between the sizing roller and the squeezing rolls a sufficient distance 5 to squeeze out the surplus sizing substance from the yarn, the said last named mechanism comprising standards, said standards including vertically extensible members, side arms rockably mounted on the standards, 10 transverse guide rollers mounted on the ends of the said side arms and over which the threads pass, a weighted tension element movable vertically between the said standards, and including a transverse member 15 adapted for passing down between the thread guide rollers when the tension element is lowered, and means for lifting the tension element and supporting it with its transverse yarn engaging member raised 20 above the said yarn.

2. In a yarn sizing machine, the combination with the sizing tank, the sizing roller, the squeezing rolls, the means for drawing the yarn through the rolls and a tension device to hold the yarn from backward movement; of a mechanism for raising the said sizing roller from immersion and advancing the yarn between the sizing roller and squeezing rolls a sufficient distance to 25 squeeze out the surplus sizing substance from the yarn, the said mechanism comprising standards that include upper extensible sections, each of which has a groove extending the full length thereof, rocker arms pivotally mounted on the said standard sections, transverse guide rollers journaled in the ends of the rocker arms for engaging the yarn threads, a weighted extension element mounted on the standards and having 30 vertical movement between the standards, the said element including members slideable in the grooves of the standards, a cross bar journaled between the said slideable members and adapted when the members are 35 moved downwardly to engage the yarn threads and carry them down in a loop form between the transverse guide rollers on the rockable arms, lifting members hingedly connected to the upper ends of the said 40 slideable members and adapted for being swung over the upper ends of the standards to hold the said slideable members and the cross member when the latter is elevated 45 above the yarn threads.

3. A slack take-up mechanism for yarn sizing machines comprising a pair of oppositely disposed standards each consisting of a lower and fixedly held portion, and an upper portion vertically adjustable upon the 50 said lower portion, the said upper portions of the standards having a continuous groove on the inner face thereof and a series of vertically disposed apertures in the upper ends thereof, a cross arm for each of the upper

sections, a pivotal connection that joins the 65 said arms with the said upper sections, transverse guide rollers, a pair of oppositely disposed slide bars mounted in the grooves of the said upper sections, a transverse presser member secured to the slide bars 70 and adapted, when the yarn is passing over the transverse guide rollers for being moved down between the said rollers to form a loop and draw the threads between the squeezing rolls and a lifting member slidably connected to the slide bars and adapted 75 when the bars are lifted to swing over the upper ends of the standards to hold the slide bars up and to swing into alignment with the slide bars to move with the said bars in the standard grooves. 80

4. In a sizing machine of the class described, the combination of a sizing tank, a sizing roller movable vertically in the tank, a drying cylinder, squeeze rollers disposed in the line of feed of the threads between the said squeezing roller and the drying cylinder, guide standards arranged in the line of feed of the threads between the squeeze rolls and the drying cylinder, side arms rockably mounted on the guide standards, transverse guide members over which the threads pass, the said guide members being journaled in the ends of the rockably mounted arms, and a weighted tension element that includes 90 means for engaging the standards to normally hold the said element out of contact with the threads, the said element being adapted when released to travel on the side standards down between the aforesaid transverse guide members to carry the threads below the said guide members to form a bight or loop in the yarns and tension the same to raise the sizing roller and cause the 95 yarns to pass between the squeeze rolls. 100

5. In a yarn sizing machine of the character stated; the combination with the sizing rollers and means for drawing the yarn through the rolls and other means for holding the yarn from backward movement; of a mechanism for raising the said sizing roller from immersion and advancing the yarn between the sizing roller and the squeezing rollers a sufficient distance to 110 squeeze out the surplus sizing substance from the yarn, the said mechanism comprising a pair of oppositely disposed standards, each of which includes an upper extensible section having a vertical groove that extends the full length thereof, a pair of 115 rocker arms pivotally and adjustably mounted on the said extensible standard members, transverse yarn guide rollers journaled in the opposite ends of the said rocker arms, a weighted extension element mounted on 120 the grooved standard members, the said element including members slideable in the groove of the said standard members, and 125

weighted arms hingedly journaled with the members that slidably engage the aforesaid grooved standards and are adapted to be extended in alinement with the said slidable members when it is desired to lower the weighted extension element to take up the slack in the yarn, and adapted to be swung out at right angles to the said slidable mem-

bers to rest upon the upper ends of the grooved standard sections to thereby hold ¹⁵ the weighted member from dropping down between the said standards.
